AERONAUTICAL WHEEL

Robert J. McLaughlin, Brooklyn, N. Y.

Application November 8, 1934, Serial No. 752,163

4 Claims. (Cl. 170—141)

My invention relates to the navigation of the air and to the space above the air. It is a supporting device for air ships and employs a rarefied condition, maintained by centrifugal force, to lift the air ship into the air.

The objects of my invention are; first, to create a vortex around a stationary hub; second, to develop a compression inside the hub; third, to discharge the air through a vent in the lower surface of the hub; fourth, to drive a revolving stream of air through the discharged current of air; fifth, to supply compressed air to the vortex below the hub; and sixth, to secure a lifting force by unequal atmospheric stress inside the aeronautical wheel.

I attain the objects of my invention by the mechanism illustrated in the accompanying drawings, in which Fig. 1 is a perspective view of the aeronautical wheel, with parts removed, showing the interior arrangements; Fig. 2 is a side elevation of the aeronautical wheel; Fig. 3 is a cross section of the aeronautical wheel; and, Fig. 4 is a vertical section of the aeronautical wheel.

Similar numerals refer to similar parts throughout the several views.

Two annular plates 1 and 2 are fastened together by a series of curving, radial vanes 3, forming an aeronautical wheel, which is mounted on a fixed horizontal shaft 4. The wheel is supported on the shaft by means of two screw propellers 5 and 6 whose blades are provided with extensions 7 which are fixed to the annular plates 1 and 2. The blades of the propellers 5 and 6 serve as the spokes of the aeronautical wheel.

The propellers 5 and 6 revolve rapidly on the bearings 8, 9 and 10, Fig. 4, in the direction indicated by the arrows, Fig. 3, and as they are pitched in opposite directions to impel the air inwardly, drive a current of air into the stationary hub 11 in an axial direction, so that there is an impact of the air inside the hub 11, and a resulting compression of the air. The impact is important for the success of the machine, as it not only delays the stream of air but destroys its kinetic energy. This is necessary because the descending stream of air gives a downward pull to the air ship.

The kinetic energy is changed into the potential energy of compressed air, which changes immediately into the kinetic energy of the downward discharge of air. This operation momentarily delays the descending current of air and lessens its downward drag on the air ship. From the

compression of the air in the hub 11 the stream is driven downward through a vent 12 in the base of the hub 11.

This hub is mounted on the fixed horizontal shaft 4 by means of four interior spokes 13, Figs. 3 and 4.

The vanes 3 carry a fixed body of air around the outer surface of the stationary hub 11. This air cannot escape from the aeronautical wheel because of the atmospheric pressure at the circumference of the wheel, and because of the suction of the partial vacuum maintained at the outer surface of the hub 11. This suction is caused by the rapid rotation of the aeronautical wheel and the resulting centrifugal force acting on the fixed body of rarefied air.

The vanes 3 carry this revolving body of rarefied air across the path of the compressed air discharged downward through the vent 12, and the condition of rarefaction in the revolving body 20 of air is thus destroyed below the stationary hub 11. This sudden change from rarefaction to compression in the revolving body of air permits the suction above the hub 11 to pull the hub upward with a force of several tons. The strain 25 comes on the heavy supporting spokes 13, which are attached to the fixed horizontal shaft 4, and is carried down to the floor supports 14.

The inner edges of the vanes 3 come very close to the outer surface of the stationary hub 11, and the compressed air below the vent 12 is not carried above the hub 11. The rarefaction at the outer and upper surface of the hub is constantly maintained by centrifugal force acting on the air revolving around the hub.

The compression inside the hub 11 will amount to about one pound per square inch when the diameter of the hub is about six feet and the screw propellers are making eighteen hundred revolutions per minute. In this case the aeronautical wheel will be about fourteen feet in diameter and at the high speed mentioned above an enormous suction will be developed above the stationary hub 11. It will amount to about 11 pounds per square inch and give a total upward 45 pull of about twenty tons. To this will be added about two tons of upward push from the compression inside the hub. From the upward pull the downward drag of the discharged current will be subtracted. It will not amount to more than a 50 few hundred pounds.

Very good results will be secured with an aeronautical wheel about the size indicated in the drawings, with a speed of twelve hundred revolutions per minute.

The hub 11 will be provided with two flanges 15, Fig 4, which will occupy sockets formed by two exterior flanges 16 which will be attached to the revolving plates 1 and 2. The object of these flanges is to keep the air outside the aeronautical wheel from entering the rarefied area above the hub 11 through the spaces between the lower edges of the annular plates 1 and 2 and the hub 11. These flanges 15 and 16 also serve to keep the compressed air in the hub from escaping into the rarefied area above the hub 11.

The blades of the screw propellers 5 and 6 will serve as power wheels when the velocity of the discharged air is greater than the pitch distance 15 of the screw propellers. A one to one pitch ratio will be employed.

The development of centrifugal force requires no power after a uniform speed is attained.

The efficiency will be increased by making the 20 wheel large, and by enlarging the diameter of the hub 11 without increasing the size of the vanes 3 a considerable increase in lift will result, but more power will be required with a larger hub.

25 The actual movement of the air downward will have a reaction more or less in harmony with Newton's second law of motion, but this so called law deals only with positive forces and the momentum of actual movements of masses. The 30 negative lift is not the same thing. It depends upon rarefaction and the absence of air above the hub 11.

35 Due to the egress of the air discharged from the vent 12 acting upon the outside air in the path of its flow outward, a reaction will take place to bring about motion, while the compression inside the hub 11 or the partial vacuum outside of the hub 11 are balanced by the other reactions.

Having described my invention what I claim is:

40 1. An aeronautical wheel for air ships consisting of a rapidly revolving annular rotor, an annular space in the said wheel for the development of rarefaction in the air contained in the annular space, radial curving vanes, serving as turbine 45 blades when acted upon by a current of air discharged downward from the axis of the annular wheel, and serving as fans when rotating the air contained in the said annular space; two vertical, annular, parallel plates forming the annular space 50 in the said annular wheel and connected rigidly to the said radial curving vanes; a fixed horizontal shaft, a cylindrical hub connected to said fixed shaft, circular and rectangular vents in said hub for passing of air through the hub and thence 55 through the lower portion of the space in said wheel, and bearings in the opposite ends of the shaft, on which the said annular wheel revolves, and vertical, standing supports on opposite sides of the said annular wheel, rigidly connected, on one side, to the horizontal shaft, and on the other side, connected by bearings, to the shaft, substantially as described.

60 2. A vacuum rotor for air ships consisting of an annular wheel, an annular space in the said wheel, radial curving vanes set rigidly in the an-

nular space, two vertical, annular plates connected rigidly to the said vanes; a fixed horizontal shaft, bearings in the opposite ends of the shaft for the rotation of the said annular wheel; vertical, standing supports for the horizontal shaft, 5 rigidly connected to the shaft on one side, and connected to the shaft on the other side by bearings; a fixed cylindrical hub occupying the axial space in the said annular wheel, a plurality of supporting spokes rigidly connecting the hub 10 to the said horizontal shaft, circular vents at opposite ends of the cylindrical hub, a rectangular vent in the lower surface of the cylindrical hub, for the vertical, downward discharge of the air entering the hub in opposite, horizontal directions through the said circular vents, substantially 15 as described.

3. A lifting wheel for air ships, having an annular wheel, an annular space in the said wheel, radial, curving vanes, annular plates connected 20 rigidly to the vanes, a fixed, horizontal shaft, bearings in the opposite ends of the shaft for the rotation of the said annular wheel; vertical, standing supports for the horizontal shaft; a fixed cylindrical hub in the center of the annular wheel, a plurality of supporting spokes connecting the said cylindrical hub to the fixed, horizontal shaft; circular and rectangular vents in the said hub for the passage of air through the hub, and thence through the lower portion of 25 the said annular wheel; two supporting screw propellers set opposite one another on the said horizontal shaft and driving air through the circular vents to the interior of the cylindrical hub, and thence through the rectangular vent in the 30 lower surface of the hub; extensions from the propeller blades to the outer sides of the annular plates, causing the propellers, the annular plates and the radial vanes to move as one wheel around the horizontal axis shaft; a motor, a motor shaft 40 turning in a bearing set in the upper end of one of the said vertical, standing supports, and fastened rigidly to one of the screw propellers, by means of which the annular wheel and the opposite screw propeller are revolved on the horizontal 45 shaft, substantially as described.

4. A centrifugal lifting device for air ships consisting of an annular wheel, an annular space, radial, curving vanes set in the annular space, 50 annular plates fastened to the vanes; a cylindrical hub occupying the hollow space at the center of the annular wheel, circular and rectangular vents in the said hub for the passing of air through the hub, and thence through said annular space, and flanges on the circular vents of 55 the cylindrical hub, sockets on the outer surfaces of the annular plates into which the hub flanges extend without making a contact with the sockets; flanges on the outer surfaces of the annular plates forming the said sockets, and preventing 60 the entrance of air between the hub and the annular plates into the rarefied air maintained in the annular space, substantially as described.
